UNITED STATES PATENT OFFICE.

ROBERT B. CODLING, OF BRISTOL, CONNECTICUT.

SHOE-STRETCHER.

1,107,037.

Specification of Letters Patent. Patented Aug. 11, 1914.

Application filed May 7, 1913. Serial No. 766,074.

To all whom it may concern:

Be it known that I, ROBERT B. CODLING, a citizen of the United States, residing at Bristol, in the county of Hartford and State 5 of Connecticut, have invented certain new and useful Improvements in Shoe-Stretchers, of which the following is a specification.

My invention relates to improvements in 10 shoe stretchers, and the object of my improvement is to produce a stretcher that can be readily applied to a shoe so as to stretch or enlarge some particular portion thereof and that furthermore on account of the in- 15 herent resiliency in the device is suitable for being retained in position for a considerable period of time and effecting the stretching desired gradually and without forcibly damaging the material.

20 In the accompanying drawing:—Figure 1 is a plan view of my improved shoe stretcher. Fig. 2 is a side elevation of the same. Fig. 3 is a similar view of the other side. Fig. 4 is a plan view of the same in 25 opened out position. Fig. 5 is a front elevation of the holder. Fig. 6 is an enlarged fragmentary view corresponding to Fig. 3 of a modification of my shoe stretcher. Fig. 7 is a similar view of another modification. 30 Fig. 8 is a similar view of the style shown in Fig. 7 provided with a layer of cushioning material. Fig. 9 is a plan view of the same. Fig. 10 is a plan view of another modification of my shoe stretcher. Fig. 11 35 is a view corresponding to Fig. 4 and on the same scale, of a modified form of stretcher, a portion of which is shown in Fig. 6.

40 My shoe stretcher comprises a body portion 10 which is made preferably of a strip of sheet spring material formed into U-shape of suitable dimensions to be entered within a shoe and having at the outer side of the end 16 of one of the arms 14 a bearing or distributing member 11 of relatively 45 large extent and at the outer side of the end 15 of the other arm a localizing member 12 of relatively smaller extent. When the stretcher is placed in the shoe the resiliency 50 of the material of the body portion 10 serves to hold the members 11 and 12 in engagement with the walls of the shoe. The distributing member 11 may consist of a strip 55 of leather or rubber, secured to the body portion 10 in any convenient manner, as by adhesive cement or rivets 13, or both, and

serves as a positioning member to positively position the end of the arm 14 to which it is attached and also to distribute the pressure due to the resiliency of the body portion 10 over a relatively large area. The localizing member 12 may be similarly secured to the other arm 14, and as stated is relatively of smaller extent, and accordingly serves to localize the effect of the resiliency 65 of the body portion 10. As a further means of localization the end 15 having the localizing member 12 may be off-set outwardly as shown at 26.

60 In use, the localizing member 12 is positioned in contact with a portion of the wall of the shoe that it is desired to have stretched and the distributing member 11 is positioned at a suitable location to coöperate to hold the localizing member 12 in the position desired. Owing to the relatively large 70 area of the distributing member 11 the effect of the same is limited to such positioning, the pressure effect thereof being spread over a relatively wide area. The contact 75 portion of the localizing member 12 being relatively small, the effect thereof is relatively greater on the particular spot with which it is in engagement, and will accordingly operate to stretch the material of the 80 wall of the shoe. Furthermore, the effect of the localizing member 12 is intensified by moistening the leather at the spot on which it is desired to have the same operate. By placing the stretcher in position 85 in the manner described and having the same there for a period, which in some cases may be over night, my stretcher operates to stretch the leather gradually and 90 at such a moderate rate as to do this without injury to the leather.

95 As a convenience in holding the arms 14 together when not in use and also while inserting the stretcher in the shoe I may use a holder or keeper 18 which is formed of a 100 piece of wire in U-shape having the middle member 19 of length such as to give the desired amount of spread to the arms 14 and the downwardly directed branches 20 at the ends thereof suitable for engaging with the 105 arms 14. The arms 14 may be provided with mating sets of corrugations 21 for receiving and positioning the branches 19.

110 The distributing member 11^a shown in Fig. 6 consists of the surface of the arm 14^a roughened to form a gripping surface and the outer surface of the localizing member

- 12^a, shown in Fig. 11, is similarly roughened. In some cases some friction material, such as emery may be applied thereto. In Fig. 7 the distributing member 11^b consists of the face of the material of the arm 14^b roughened to form a gripping surface and longitudinally slitted to provide fingers 31 to effect the distribution of the holding pressure.
- 10 In the modification shown in Figs. 8 and 9 the arm 14^c is slitted as in the style shown in Fig. 7 to form fingers 31^a and the surface of all the fingers 31^a is covered by a single piece of friction material 11^c, which may be held in place by rivets 13^a, and which are preferably located in the upper and lower fingers 31^a. In this case the friction material 11^c may be relatively thin and flexible so as to accommodate itself to the pressure on the different fingers 31^a, which would ordinarily vary considerably due to the shape of the portions of the wall of the shoe that is opposed to the said fingers.
- 25 It is apparent that some changes from the specific construction herein disclosed may be made and therefore I do not wish to be understood as limiting myself to the precise form of construction shown and described, but desire the liberty to make such changes, in working my invention, as may

fairly come within the spirit and scope of the same. For instance, the body portion 10^a of spring material may be given a V shape in lieu of the U shape at the apex, as shown in Fig. 10. 35

I claim as my invention:—

In a shoe stretcher comprising a spring member having opposed arms, a relatively wide and elongated bearing portion at the free end of one of the said arms and serving as a distributing member, and a relatively small bearing portion at the free end of the other of the said arms and serving as a localizing member, and the said spring member being formed of flat spring material of uniform width from end to end, and bent into U shape, the outer faces of the free ends of the said spring material being roughened suitably to serve as the said distributing member and localizing member, 40 and the portion of the said spring material serving as the said localizing member being offset relatively to the body portion thereof so as to limit the said localizing member in the longitudinal direction of the said spring material. 45

ROBERT B. CODLING.
